UNITED STATES PATENT OFFICE.

RUDOLPH LEHNHOFF, OF BURNHAM, ILLINOIS.

WRENCH.

1,348,366.

Specification of Letters Patent.

Patented Aug. 3, 1920.

Application filed May 23, 1919. Serial No. 299,194.

To all whom it may concern:

Be it known that I, RUDOLPH LEHNHOFF, a citizen of the United States, residing at Burnham, in the county of Cook and State 5 of Illinois, have invented a certain new and useful Improvement in Wrenches, of which the following is a full, clear, concise, and exact description, reference being had to the accompanying drawings, forming a part of 10 this specification.

My invention relates to improvements in wrenches and has special reference to an improved monkey wrench.

The object of my invention is to provide a 15 wrench of the character known as "monkey wrench" which can be readily manipulated to permit the movable jaw to be drawn out freely, in which the said jaw shall be automatically withdrawn, and which shall be so 20 constructed that the automatic retraction of the jaw can be readily controlled to permit it to be retracted substantially instantaneously or to be retracted slowly.

A further object of my invention is to 25 provide a wrench of the character outlined, in which the coöperating screw and worm for relative movement of the two jaws of the wrench shall be normally locked in engaging relation and shall have a simple trigger release.

My invention consists in a wrench having 30 two relatively movable jaws, screw means for adjusting said jaws, trigger means for releasing the screw means for permitting the 35 free relative movement of the jaws, spring means for closing the jaws and means for controlling the action of the spring in closing the jaws.

My invention also consists in the several 40 features of construction and in the combinations and relations of parts whereby I am enabled to attain the above-mentioned and other objects and all as hereinafter described, and particularly pointed out in the 45 appended claims.

For a clear understanding of my invention, attention is directed to said drawings, in which:

Figure 1 is a longitudinal sectional view 50 substantially on the line 1—1 of Fig. 3 and showing the two jaw members on the wrench in closed relation and side elevation;

Fig. 2 is a view similar to Fig. 1 but showing the jaws of the wrench separated; and

Figs. 3 and 4 are detailed cross-sectional 55 views taken substantially on the lines 3—3 and 4—4 of Fig. 1.

The wrench comprises the two main members 5 and 6, the member 5 being provided with a jaw 7 and the member 6 with a co-operating jaw 8. These members are arranged parallel with each other and the member 5 with its jaw 7 can be moved longitudinally relatively to the member 6 to open the wrench as shown in Fig. 2 or to 60 close the wrench as shown in Fig. 1.

To hold the members parallel and permit longitudinal movement I provide a sheet metal U-shaped casing 9 having sides 10 and a back 11 and open at its front. This casing 70 receives the members 5 and 6 between its sides and its sides are rigidly secured to the member 6 by rivets 12 and 13 and provides the housing in which the member 5 is longitudinally movable. This casing does not 75 inclose the jaws 7 and 8, which are thus free to engage the article upon which the wrench is to be used. I close the rear end of the casing by a filler end block 14, which is of even thickness with the members 5 and 6 80 and is rigidly held in position by rivets 15.

The member 6 extends only part way back toward the rear end of the wrench and between its rear end and the filler block 14 I provide a pivotally mounted block 16 which 85 is mounted at its rear end on the rivet 13 so that it can swing from and toward the member 5.

For the purpose of locking the member 5 with its jaw 7 relatively to the member 6 90 and its jaw 8 so that the jaws cannot separate, in use, I provide a worm screw 18 rotatably carried by the block 16 and adapted to be swung with the block into and out of mesh with a screw rack 19 which I form on 95 the inner edge of the shank 17 of the member 5. The block 16 has an opening 20 to receive the worm and the worm is rigidly carried on a shaft 21 which is rotatably mounted in the member 16 at the forward 100 end of the notch 20 and its rear end passes through a hole 22 which I provide in the filler block 14. The rear end of the shaft 21 projects beyond the block 14 and I se-

cure a knurled head or button 23 on the outer end of the shaft and by which the worm screw 18 can be rotated to adjust the jaws from and toward each other when the 5 screw is in mesh with the rack.

I pivotally mount the block 16 as described so that I can release the rack from the screw, as shown in Fig. 2, to permit the quick and free relative movement of the 10 outer jaw 7 to open the wrench and its free inward movement to close the wrench.

For swinging the block 16 on its pivot and the screw into and out of mesh with the rack, I provide a trigger lever 24 pivotally mounted between its ends to the sides of the casing on the pivot 25 and having one end 26 arranged to engage in a notch 27 in the forward end of the block 16 and so arranged that when the trigger is swung 15 on its pivot the block will be swung out or on its pivot.

To lock the screw in the rack I provide an inwardly extending abutment 28 on the trigger and a co-operating outwardly extending projection 29 on the free end of the 20 block 16. The abutment 28 is in the path of the projection 29 as the member 16 swings out and prevents the swinging of the member 16 until the trigger has been swung on its pivot sufficient to permit the projection 29 to pass the abutment 28 as shown in Fig. 2.

It is to be noted that the line of pressure of the contact of the projection 29 against 35 the abutment 28 passes substantially through the pivot 25 of the trigger 24 and that consequently the locking pressure does not tend to rotate the trigger and release the worm. There is sufficient clearance between the end 40 26 of the trigger 24 and the walls of the notch to permit the trigger to swing the abutment 28 out of the path of the projection 29 before the same contacts with the outer end thereof. The trigger 24 is normally held in a locking position by a flat 45 spring 30 mounted in an opening 21 provided in the rear end of the member 6 and having its free end clamped in a slot 32 provided in the member 6. The spring 30 bears 50 at its free end upon the finger end 33 of the trigger 24 and tends to hold said end outwardly, as shown in Fig. 1, where it can be conveniently pressed by the finger of the user to release the worm and rack.

In order to cause the worm 18 to be moved inwardly in advance of the engagement of the abutment 28 and projection 29, I provide a light spring 30 substantially parallel with the spring 30 and long enough 55 so that its free end projects between the projection 29 and abutment 28 and formed to bear upon the outer end of the projection 29 to yieldingly hold the block 16 swung inwardly as far as the engagement of the trigger therewith will permit. In consequence 60

of this the clearance between the end 26 of the trigger 24 and the walls of the notch 27 the block 16, with the worm 20, is swung inwardly quick enough so that the projection 29 clears the abutment 28 as the trigger 70 swings back to locking position.

To cause the member 5 to be automatically retracted once it has been drawn out, as shown in Fig. 2, I provide a compression spring 34 mounted in an elongated notch 35 75 which I provide in the back edge of the shank 17 of the member 5. The forward end 36 of the spring 34 abuts a projection 37 secured to the rear wall 11 of the casing 9 and the rear end 38 of the spring 34 abuts 80 a projecting part 39 of the shank 17 of the member 5, consequently when the member 5 is withdrawn the spring is compressed and tends to push the member 5 back again.

I make the spring 34 tapered as shown so 85 that I can make the notch 35 correspondingly tapered in order that the shank 17 at the forward end of the notch 35 will be as strong as possible. I guide this spring upon a rod 40 which is so mounted at its forward 90 end in the projection 37 that its rear end is threaded through a hole 41 in the projection 39. I make the forward end of the rod smaller than the rear end to accommodate the smaller diameter of the spring at this 95 end and I provide a shoulder 42 on the rod against which the projection 39 contacts to limit the outward movement of the jaw 7.

Once the jaw 7 has been drawn out the spring 34 will retract it unless the member is 100 held either by being placed upon the article, as a nut upon which it is to be used or is held in some other way. The means which I provide to control the retraction of the jaw 7 consists of a pin 43 freely movable in 105 an opening 44 in the member 6 and provided with a head 45 at its inner end adapted to frictionally engage the adjacent edge of the shank 17 of the member 5. This frictional engagement is caused by the further 110 inward movement of the free end of the spring 30 after the trigger has been swung far enough to release the worm from the rack.

The operation is as follows: The wrench 115 being closed, the user presses the trigger inwardly thus releasing the worm from the rack and then draws the member 5 outwardly against the retracting action of the spring 34, and then presses the pin 43 into 120 contact with the member 5 to hold the member 5 against the withdrawing action of the spring 34. He then places the jaws of the wrench on opposite sides of the bolt head or nut to be engaged and releases the pressure on the pin 43 sufficient to permit the spring 34 to retract the member 5 until the jaws substantially fit the article engaged. It is obvious that if he relieves the pin 43 of all pressure the member 5 will be in- 125 130

stantaneously retracted with the whole force of the spring 34, it is also obvious that by maintaining some frictional engagement between the pin 43 and the member 5 the retraction of the member 5 can be controlled as desired. If a highly finished article is to be engaged, it might mar it to have the member 5 retracted with a hammer-like blow. Having allowed the member 5 to be withdrawn so that the jaws are in position to engage the article, the trigger is entirely relieved and the worm is forced back into contact with the rack by the spring 30 and the coöperating projections 28 and 29 lock the worm in mesh. It is obvious, if at this time the worm should not enter freely into the rack, that a slight rotation of the worm by means of the knurled head or button 23 will cause the thread of the worm to mesh with the teeth of the rack and the worm would then be forced into mesh by the spring 30. If the wrench does not now fit the nut or bolt head closely enough the jaws can readily be adjusted by rotating the worm 18 by means of the knurled head or button 23 to cause the desired engagement of the jaws upon the article being manipulated.

As many modifications of my invention will readily suggest themselves to one skilled in the art I do not limit or confine my invention to the specific structures herein shown and described.

I claim:

- 85 1. In a wrench of the kind described, two relatively movable members, a screw and rack connection for relatively moving members and for holding them in relatively adjusted positions, trigger means for locking the screw in the rack and for swinging the screw out of the rack, a spring resisting separation of the jaws of the wrench, and a friction member movable by said trigger for controlling the closing action of said spring.
- 40 2. In a wrench of the kind described, a screw and rack for relatively moving the two jaw members to adjust the jaws, means for releasing the screw and rack, means for normally locking the screw and rack in engaging relation, a spring for yieldingly resisting the separation of the jaws, and

means for applying friction between the two members for controlling the closing action of said spring.

55

3. In a wrench of the character described, two relatively movable jaw members, a rack on one member and a coöperating screw carried by the other member, a pivotally mounted block in which said screw is rotatably mounted, an operating lever pivotally mounted between its ends on said second mentioned member, a projection on the lever engaging in a slot in the free end of said block for releasing the screw from the 60 rack, and coöperating parts on the block and lever alined with the pivot of said lever for locking the screw in the rack.

65

4. A wrench comprising two relatively movable members, each carrying a jaw, a 70 rack on one member and a coöperating screw carried by the other member for relatively moving said members, a spring yieldingly holding the jaws against separation, a pivoted block in which the screw is rotatably mounted, means for locking the block with the screw and rack in mesh, means for unlocking and swinging said block on its pivot to release the screw from the rack, and means for frictionally engaging the 80 two members to control the action of the spring in closing the jaws.

75

5. In a wrench of the kind described, two relatively movable members each having a jaw, a rack on one member and a coöperating 85 rotatable screw carried by the other member for relatively moving said members and for holding them against relative movement, a spring tending to close said jaws together, a pivoted block in which the 90 screw is mounted, a pivoted trigger for releasing the screw from the rack, the trigger having three operating positions, and adapted in one position to lock the screw in the rack, in an intermediate position to lift 95 the screw out of the rack, and means engageable by the trigger in its third position for frictionally engaging the rack member to prevent the retraction of the rack member by said spring.
